SERVICE VEHICLE

James P. Kohls, Detroit, Mich., assignor to Jervis B. Webb
Company, a corporation of Michigan

Filed Mar. 17, 1967, Ser. No. 6,274

Term of patent 14 years

(Cl. D14—3)

The dominant features of my design reside in the portions shown in full line.

I claim:

The ornamental design for a service vehicle, as shown and described.
